UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-HANDLING MACHINE.

1,254,876.

Specification of Letters Patent. Patented Jan. 29, 1918.

Application filed November 12, 1914. Serial No. 871,848.

To all whom it may concern:

Be it known that I, HOWARD M. BARBER, a citizen of the United States, and resident of Stonington, in the county of New London 5 and State of Connecticut, have invented a new and useful Improvement in Sheet-Handling Machines, of which the following is a specification.

One object of this invention is to provide 10 means whereby a signature is stitched while at rest and is then removed from the stitcher table at a speed sufficient to cause it to clear the next succeeding signature as it is fed onto the stitcher table, such arrangement 15 permitting the stopping of the signature on the stitcher table a sufficient time to allow it to be accurately stitched.

Another object is to provide means for adjusting the opening and closing movements 20 of the grippers on the cylinder which takes the stitched signature from the stitcher table and folds the signature, so that the grasping and releasing moments of the grippers may be timed with respect to the folding 25 operation while the machine is in operation, for insuring the accurate folding of the stitched signature.

A practical embodiment of my invention is represented in the accompanying drawings, in which that part of a sheet handling machine is illustrated which includes my invention.

Figure 1 is a vertical central section taken from front to rear through the machine,

Fig. 2 is a detail vertical section taken from front to rear just inside the near side frame,

Fig. 3 is a detail similar section taken just inside the far side frame,

Fig. 4 is a detail section showing the driving connection between certain of the parts,

Fig. 5 is a detail section taken just outside the near side frame and showing the driving connection between certain other of the 45 parts,

Fig. 6 is a section showing the device for adjusting the pins which control the operation of the grippers on the folding off cylinder in side elevation,

Fig. 7 is a section showing the said device in front elevation,

Fig. 8 is a section taken in the plane of

the line A—A of Fig. 7, looking in the direction of the arrows, and

Fig. 9 is a detail section similar to Fig. 7 55 with certain of the parts removed and other parts broken away.

The stitcher table is denoted by 1, the stitcher by 2, and its driving shaft by 3, which stitcher may be of any well known or 60 approved construction adapted to stitch a signature while the movement of the signature is arrested.

The signature transfer cylinder 4 is mounted on a shaft 5 and its set of grippers 6 is arranged to transfer the signature to the set of grippers 7 of the transfer cylinder 8 mounted on the shaft 9. The signature is delivered from the transfer cylinder 8 between two sets of endless tapes 10, 11, which tapes 70 serve as a carrier for feeding the signature from the cylinder 8 onto the stitcher table 1 into engagement with a movable sheet stop 12. The endless tapes 10 pass around the cylinder 8 and the pulleys 13, 14. The endless tapes 11 pass around the pulleys 15, 16, 17, 18. The sheet stop 12 is mounted on a rock shaft 19 to which is fixed a rock lever 20 having a stud or roller 21 under the control of a rotary cam 22 rotating with the 80 male folding cylinder 23. This cylinder 23 has a set of tumbler actuated grippers 24 and the floating tucking blade 25 of a folding mechanism.

The female folding cylinder 26 carries the 85 floating folding jaws 27 of the folding mechanism.

The shaft of the male folding cylinder 23 is denoted by 28 and the shaft of the female folding cylinder 26 is denoted by 29. 90

A suitable delivery mechanism is employed for delivering the stitched signatures from the female folding cylinder 26, which delivery mechanism, in the present instance, comprises the two sets of endless tapes 30, 95 31, the endless tapes 30 passing around the cylinder 26 and the pulleys 32, 33, and the endless tapes 31 passing around the pulleys 34, 35, 36. The signatures are delivered from the delivery tape carriers onto a proper delivery mechanism 37 from whence the signatures are dropped onto the tapes 38 of an endless delivery carrier, which tapes pass around suitable pulleys 39, 40. 100

The transfer cylinders 4 and 8, the tape carriers 10 and 11, and the stitcher 2, are driven through the train of gears 41, 42, 43, 44, 45, 46, 47, 48, 49.

5 The male folding cylinder 23 is driven from the vertical shaft 50 through the train of gears 51, 52, 53, 54, 55, 56, to which last-named gear the rotary cam 22 is fixed.

10 The female folding cylinder 26, the endless tape carriers 30, 31, and the dropper delivery mechanism 37 are driven through the train of gears 57, 58, 59, 60, 61, 62, 63.

15 The endless delivery carrier 38 is driven from the shaft 29 of the female folding cylinder 26 through the bevel gears 64, 65, shaft 66, worm gears 67, 68, and spur gears 69, 70.

20 The relative speeds of the driving mechanisms hereinabove referred to, are such that the stitched signatures are withdrawn from the stitcher table at a speed equal to or greater than the speed of the press thus giving ample time for the stitching of the signature while it rests on the stitcher table and the removal of the stitched signature without interfering with the oncoming next succeeding unstitched signature.

In the relationship of the parts as shown in the accompanying drawings, the shafts 5 30 and 9 of the transfer cylinders, are driven at the same speed as the shafts 28 and 29 of the folding cylinders. The stitched signature in this instance will be removed from the stitcher table at a greater speed than its feeding in movement because of the larger circumference of the male folding cylinder 23. The movable sheet stop 12 is held in its stopping position about one-half the revolution of the male folding cylinder 23 and 40 in its released position the other half of the revolution of the said folding cylinder.

45 The cam mechanism for controlling the floating of the tucking blade and folding jaws in parallelism during the folding of the signature off from the male folding cylinder 23 onto the female folding cylinder 26 will not be specifically described herein as it is of well known and approved construction and forms no part of the present invention.

50 I employ adjustable means for closing the grippers 24 on the male folding cylinder 23 at their signature receiving point and for opening the grippers at their signature releasing point so that the position of the signature with respect to the folding device to insure an accurate folding of the signature may be regulated without disturbing the operation of the folding device or the operation of the machine.

55 The adjustable means which I have herein illustrated is constructed, arranged and operated as follows: The shaft 71 of the grippers 24 is provided with a tumbler cam

72 which is engaged by the pin 73 at the 65 signature receiving position of the grippers and by the pin 74 at the signature releasing position of the said grippers. The pin 73 is carried by a bracket 75 fitted to slide on a stationary bracket support 76. The pin 70 74 is carried by a bracket 77 fitted to slide on a stationary bracket support 78.

A gib 79 serves to hold the bracket 75 in position on its support 76 and a gib 80 serves to hold the bracket 77 in position on its support 78. These brackets 75, 77, with their pins 73, 74, are movable concentric with the shaft 28 of the male folding cylinder 23 so as to keep the pins 73, 74, at all times in their proper radial position with respect to the gripper tumbler cam 72. The bracket 75 and its pin 73 are adjusted circumferentially by an eccentric cam 81 on a shaft 82 mounted in the bracket support 76 and gib 79, which shaft is turned from a hand shaft 83 through a worm and gear connection 84, 85. This hand shaft 83 is mounted in a bracket 86 secured by bolts 87 to the support 76.

80 Similarly, the bracket 77 and its pin 74 is adjusted circumferentially by an eccentric cam 88 on a shaft 89 mounted in the support 78 and gib 80, which shaft is turned from a hand shaft 90 through a worm and gear connection 91, 92. This hand shaft 90 95 is mounted in a suitable bracket 93, secured to the support 78 by bolts 94. The handles of the shafts 83 and 90 are denoted, respectively, by 95 and 96. The gib 79 is secured to the bracket support 75 by the bolts 100 97 and the gib 80 is secured to the support 78 by the bolts 98.

100 The supports 76 and 78 are independently adjustable in a rotary direction on the side frame, in the present instance, by providing the frame and the supports with holes 99, 105 100, engaged by adjusting bolts 101.

110 By the term "cylinder" as used in the description, I contemplate any suitable means for passing the sheets and signatures through the prescribed paths and by the term "grippers" I wish to include any engaging devices suitable for the purpose of leading the sheets or signatures through said prescribed paths.

115 It will be seen from the above description that the signature may be stopped a sufficient length of time to be properly stitched and is then removed by a device which will start it off the stitcher table at a speed 120 which will insure its free removal from the stitcher table without interfering with the incoming unstitched signature.

125 It will also be seen that by the provision of stationary means for adjusting the operation of the grippers on the folding off cylinder, the accurate folding of the stitched signature may be accomplished without stop-

ping the machine or interfering with its operation.

The adjustable means for controlling the operation of the grippers on the male folding cylinder, shown and described but not claimed specifically herein, forms the subject-matter of my copending divisional application filed February 26, 1916, Serial No. 80663.

10. What I claim is:

1. A stitcher mechanism, means for feeding signatures thereto, movable means independent of the stitcher mechanism for arresting the movement of the signatures during the stitching operation, rotary means including grippers for positively removing the stitched signatures from the stitcher mechanism in the line of their travel to the stitcher mechanism, and means for

20 folding and delivering said signatures.

2. A stitcher mechanism, means for feeding signatures thereto, at a certain speed, movable means independent of the stitcher mechanism for arresting the movement of

25 the signatures during the stitching operation, and means for positively removing the stitched signatures from the stitcher mechanism in the line of their travel to the stitcher mechanism, at a speed equal to or greater

30 than their feeding-in speed.

3. A stitcher mechanism, means for feeding signatures thereto at a certain speed, movable means independent of the stitcher mechanism for arresting the movement of

35 the signatures during the stitching operation, means for positively removing the stitched signatures from the stitcher mechanism in the line of their travel to the stitcher mechanism, at a speed equal to or greater

40 than their feeding-in speed and means for folding and delivering said signatures.

4. A stitcher mechanism, means for feeding signatures thereto at a certain speed, movable means independent of the stitcher

45 mechanism for arresting the movement of the signatures during the stitching operation and rotary means including grippers for positively removing the stitched signatures from the stitcher mechanism in the

50 line of their travel to the stitcher mechanism, at a speed equal to or greater than their feeding-in speed.

5. A stitcher mechanism, means for feeding signatures thereto at a certain speed, movable means independent of the stitcher mechanism for arresting the movement of

55 the signatures during the stitching operation, rotary means including grippers for positively removing the stitched signatures

60 from the stitcher mechanism in the line of their travel to the stitcher mechanism, at a speed equal to or greater than their feeding-in speed and means for folding and de-

livering said signatures.

6. A stitcher mechanism, means for feeding signatures thereto, movable means independent of the stitcher mechanism for arresting the movement of the signatures during the stitching operation and means for positively removing the stitched signatures from the stitcher mechanism in the line of their travel to the stitcher mechanism, and folding the signatures comprising rotary folding cylinders, coacting folding devices carried thereby and signature receiving and releasing grippers carried by the folding-off cylinder.

7. A stitcher mechanism, means for feeding signatures thereto, movable means independent of the stitcher mechanism for arresting the movement of the signatures during the stitching operation, means for positively removing the stitched signatures from the stitcher mechanism in the line of their travel to the stitcher mechanism, and folding the signatures comprising rotary folding cylinders, coacting folding devices carried thereby and the signature receiving and releasing grippers carried by the folding-off cylinder, and devices for controlling the operation of the grippers at their receiving and releasing points.

8. A stitcher mechanism, means for feeding signatures thereto, movable means independent of the stitcher mechanism for arresting the movement of the signatures during the stitching operation, means for positively removing the stitched signatures from the stitcher mechanism in the line of their travel to the stitcher mechanism, and folding the signatures comprising rotary folding cylinders, coacting folding devices carried thereby and the signature receiving and releasing grippers carried by the folding-off cylinder, devices for controlling the operation of the grippers at their receiving and releasing points, and means for independently adjusting the said devices for adjusting the fold line in the signatures.

9. A stitcher mechanism, means for feeding signatures thereto, movable means independent of the stitcher mechanism for arresting the movement of the signatures during the stitching operation, means for positively removing the stitched signatures from the stitcher mechanism in the line of their travel to the stitcher mechanism and folding the signatures comprising rotary folding cylinders, coacting folding devices carried thereby and the signature receiving and releasing grippers carried by the folding-off cylinder, devices for controlling the operation of the grippers at their receiving and releasing points, and means for independently adjusting the said devices for adjusting the fold line in the signatures, while the cylinders are rotating.

10. A stitcher mechanism, means for feed-

- ing signatures thereto, movable means independent of the stitcher mechanism for arresting the movement of the signatures during the stitching operation, a rotary cylinder having grippers thereon for positively removing the stitched signatures in the line of their travel to the stitcher mechanism, and means for adjusting the point where the grippers engage the signature.
- 10 11. A stitcher mechanism, means for feeding signatures thereto, movable means independent of the stitcher mechanism for arresting the movement of the signatures during the stitching operation, a rotary cylinder

having grippers thereon for positively removing the stitched signatures in the line of their travel to the stitcher mechanism, and means for adjusting the point where the grippers engage the signature, while the cylinder is rotating.

In testimony, that I claim the foregoing as my invention, I have signed my name in the presence of two witnesses, this tenth day of November, A. D. 1914.

HOWARD M. BARBER.

Witnesses:
